101,302

DESIGN FOR A TEXTILE FABRIC OR SIMILAR ARTICLE OF MANUFACTURE

John F. Gaul, Jr., Clifton, N. J., assignor to
Botany Worsted Mills, Passaic, N. J., a corpora-
tion of New Jersey

Application June 19, 1936, Serial No. 63,388

Term of patent 14 years

To all whom it may concern:

Be it known that I, John F. Gaul, Jr., a citizen of the United States of America, residing at No. 1110 Van Houten Avenue, in the town of Clifton, State of New Jersey, have invented a new, original, and ornamental Design for a Textile Fabric or Similar Article of Manufacture, of which the following is a specification, reference being had to the accompanying drawing, forming a part thereof, and showing a face view of a piece of textile fabric embodying my design.

The characteristic feature of the design resides in the arrangement of alternate series of vertical ribs or stripes formed of thickened threads, the alternate series being in groups of two and groups

of four of such ribs extending vertically on the face of the fabric, and lengths of threads of greater thickness than those forming said ribs constituting knobby ridges of substantial length disposed between said alternate series of vertical ribs or stripes, the lengths of said knobby ridges being substantially the same and separated by vertical spaces of substantially equal length.

The repeat unit is indicated between the broken lines shown in the drawing.

I claim:

The ornamental design for a textile fabric or similar article of manufacture substantially as shown and described.

JOHN F. GAUL, JR.
